DOILY OR THE LIKE

Emily L. Melson, Mamie, N. C.

Application December 7, 1949, Serial No. 6,464

Term of patent 3½ years

(Cl. D3—9)

To all whom it may concern:

Be it known that I, Emily L. Melson, a citizen of the United States, residing at Mamie, in the county of Currituck and State of North Carolina, have invented a new, original, and ornamental Design for a Doily or the like, of which the following is a specification, reference being had to the accompanying drawing, forming a part thereof.

In the drawing the figure is a plan view of a doily or the like, showing my new design.

The doily is shown against a black background to better bring out the details of the design.

I claim:

The ornamental design for a doily or the like, substantially as shown and described.

EMILY L. MELSON.
